(57) **CLAIM**

The ornamental design for a cup holder, as shown and described.

DESCRIPTION

FIG. 1 is a top perspective view of a cup holder, shown in an environmental use, showing my new design;

FIG. 2 is a bottom perspective view thereof, shown in an environmental use;

FIG. 3 is a front view thereof, shown in an environmental use;

FIG. 4 is rear view thereof, shown in an environmental use;

FIG. 5 is a left side view thereof, shown in an environmental use;

FIG. 6 is a right side view thereof, shown in an environmental use;

FIG. 7 is a top plan view thereof, shown in an environmental use;

FIG. 8 is a bottom view thereof, shown in an environmental use;

FIG. 9 is a top perspective view thereof, shown in an alternate environmental use;

FIG. 10 is a bottom perspective view thereof, shown in an alternate environmental use;

FIG. 11 is a front view thereof, shown in an alternate environmental use;

FIG. 12 is a rear view thereof, shown in an alternate environmental use;

FIG. 13 is a left side view thereof, shown in an alternate environmental use;

FIG. 14 is a right side view thereof, shown in an alternate environmental use;

FIG. 15 is a top plan view thereof, shown in an alternate environmental use; and,

FIG. 16 is a bottom plan view thereof, shown in an alternate environmental use.

The broken lines showing the environmental subject matter in FIGS. 1-16 form no part of the claimed design.

1 Claim, 16 Drawing Sheets
